US0D1108317S

(12) **United States Design Patent** (10) Patent No.: **US D1,108,317 S**
(45) Date of Patent: ** Jan. 6, 2026

(54) **TRICYCLE WITH SPARK GENERATING DEVICE**

(71) Applicant: **RAZOR USA LLC**, Cerritos, CA (US)

(72) Inventors: **Robert Chen**, San Marino, CA (US);
Seth Calvin, San Marino, CA (US);
William Griggs, Anaheim, CA (US)

(73) Assignee: **Razor USA LLC**, Cerritos, CA (US)

(**) Term: **15 Years**

(21) Appl. No.: **29/939,859**

(22) Filed: **Apr. 29, 2024**

Related U.S. Application Data

(63) Continuation of application No. 29/653,261, filed on Jun. 13, 2018, now abandoned, which is a continuation of application No. 29/592,672, filed on Feb. 1, 2017, now abandoned, which is a continuation of application No. 29/539,992, filed on Sep. 18, 2015, now abandoned, which is a continuation of application No. 29/501,947, filed on Sep. 10, 2014, now abandoned, which is a continuation of application No. 29/440,955, filed on Dec. 28, 2012, now abandoned, which is a continuation of application No. 29/422,539, filed on May 22, 2012, now abandoned, which is a continuation of application No. 13/440,761, filed on Apr. 5, 2012, now Pat. No. 8,746,723.

CLAIM

The ornamental design for a tricycle with spark generating device, as shown and described.

DESCRIPTION

FIG. 1 is a rear perspective view of a tricycle with spark generating device;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.
